RAILWAY TRAFFIC CONTROLLING
APPARATUS

Lester E. Spray, Wilkinsburg, Pa., assignor to The
Union Switch & Signal Company, Swissvale,
Pa., a corporation of Pennsylvania

Application July 15, 1930, Serial No. 468,099

5 Claims. (Cl. 246—160)

My invention relates to railway traffic controlling apparatus, and particularly to apparatus of the type involving a railway switch and a signal governing traffic over the switch.

5 One feature of my invention is the provision of novel and improved means operating when the signal has been cleared and a train is approaching the signal to prevent the operation of the switch for a given interval of time if the signal is restored to the stop position before the train has passed it.

I will describe one form of apparatus embodying my invention, and will then point out the novel features thereof in claims.

15 Referring to the drawing, the reference characters 1 and 1^a designate the rails of a railway track, which rails are divided by insulated joints 2 to form a main track section B—C and an approach track section A—B. The main section B—C contains a railway switch D operated by a mechanism E, and traffic into this section from the approach section A—B is controlled by two signals S¹ and S². These signals are in turn controlled by two signal relays H¹ and H², respectively.

20 Track section B—C is provided with a track circuit comprising a battery 3 and a track relay T¹. Section A—B is provided with a similar track circuit comprising a battery 3 and a track relay T².

25 Signal S¹ is provided with a circuit which passes from terminal X of a suitable source of current, through a front contact 4 of relay H¹, and the operating mechanism of signal S¹ to terminal Y of the same source of current. Signal S² is provided with a similar circuit including a front contact 5 of the associated relay H². Each signal relay H¹ and H² is provided with a circuit which includes a front contact 15 of track relay T¹, so that 30 when the main section B—C is occupied by a train, both of these relays will be deenergized, with the result that both signals S¹ and S² will indicate stop. The circuits for these relays are selectively controlled from a distant point 35 through apparatus having nothing to do with my present invention, which apparatus is therefore omitted from the drawing to simplify the disclosure.

40 The switch operating mechanism E is controlled in part by a front contact 16 of an approach locking relay G, it being understood that the circuit for this mechanism will also be controlled from a distant point through the medium of apparatus which is not shown in the drawing. 45 The purpose of contact 16 is to prevent switch mechanism E from being operated unless the approach locking relay G is energized.

40 The approach locking relay G is controlled in part by a slow-acting device F having an operating winding 17 and a normally open contact 10.

This device is so designed that after winding 17 becomes energized, the contact 10 will not close until the expiration of a given interval of time. The winding 17 is provided with a circuit which passes from terminal X, through back contact 6 of relay H¹, back contact 7 of relay H², back contact 12 of relay G, front contact 13 of relay T¹, back contact 14 of relay T², and the winding 17 to terminal Y.

5 The approach locking relay G is provided with a first pick-up circuit, which passes from terminal X, through back contacts 6 and 7 of signal relays H¹ and H², back contact 8 of track relay T¹, and the winding of relay G to terminal Y. This relay is provided with a second pick-up circuit, which passes from terminal X, through back contacts 6 and 7, front contact 9 of track relay T₂, and the winding of relay G to terminal Y. Relay G is provided with a third pick-up circuit, which passes from terminal X, through back contacts 6 and 7 of the signal relays, front contact 11 of relay G, and the winding of relay G to terminal Y.

10 The operation of the apparatus is as follows: Normally the signals S¹ and S² indicate stop, the track relays T¹ and T² are energized, the slow-acting device F is deenergized, and the approach locking relay G is energized. With the parts in these positions, the switch D can be operated because the circuit for mechanism E is closed at contact 16.

15 I will now assume that the circuit for relay H¹ is closed in order to clear signal S¹. Relay G will then become deenergized because its circuits will be open at back contact 6 of relay H¹, and so the switch D cannot be operated. When a 20 train moving toward the right enters section A—B, it will open track relay T², and when this train enters section B—C it will open track relay T¹. This will open the circuit for signal relay H¹, so that signal S¹ will return to the stop position, and relay G will again become energized because of its main pick-up circuit through back contacts 6, 7 and 8. It follows that when this train passes out of section B—C the parts of the 25 apparatus will be restored to the positions in which they are shown in the drawing.

30 I will now assume that signal S¹ has been cleared, that a train occupies section A—B, and that the operator at the distant point opens the circuit for relay H¹ in order to restore signal S¹ to the stop position. Relay G will remain open for a given interval of time, because its first circuit is open at back contact 8 of track relay T¹, its second circuit is open at front contact 9 of track relay T², and its stick circuit is open at its 35

own contact 11. The circuit for winding 17 of the slow-acting device F will become closed, however, as soon as back contact 6 of signal relay H¹ closes, so that after the expiration of the time required for contact 10 of this device to close, the third pick-up circuit for relay G will become closed, with the result that this relay will become energized. The switch D may then be operated.

10 It is understood that if switch D is in the reverse position and the operator desires to admit a train into section B-C, he will energize signal relay H² to clear signal S², but that the operation of the remainder of the apparatus may be the same as before.

15 One feature of my invention is the fact that the slow-acting device F never becomes energized except when it is necessary for this device to function, that is, when signal S¹ or S² is restored to the stop position while a train occupies the approach section A-B.

Although I have herein shown and described only one form of apparatus embodying my invention, it is understood that various changes and modifications may be made therein within the scope of the appended claims without departing from the spirit and scope of my invention.

Having thus described my invention, what I claim is:

30 1. In combination, a main section of railway track containing a switch, an approach section, a track circuit including a track relay for each section, a signal for said main section, a signal relay for the control of said signal, an approach locking relay for the control of said switch, a slow acting device having an energizing winding and a normally open contact, a first circuit for said approach locking relay including a back contact of said signal relay and a back contact of the 35 track relay for said main section, a second circuit for said approach locking relay including a back contact of said signal relay and a front contact of the track relay for said approach section, a third circuit for said approach locking relay including a back contact of said signal relay and the contact of said slow-acting device, a stick circuit for said approach locking relay including a back contact of said signal relay, and a circuit for the winding of said slow-acting device including a back contact of said signal relay and a back contact of said approach locking relay as well as a front contact of the track relay for the main section and a back contact of the track 40 45 50 relay for the approach section.

55 2. In combination, a main section of railway track containing a switch, an approach section, a track circuit including a track relay for each section, a signal for said main section, a signal relay for the control of said signal, an approach 60 locking relay for the control of said switch, a slow-acting device having an energizing winding

and a normally open contact, a circuit for the winding of said slow-acting device including a back contact of said signal relay and a back contact of said approach locking relay as well as a front contact of the track relay for said main section and a back contact of the track relay for said approach section, and means for controlling said approach locking relay by said signal relay and said track relays as well as by the contact of said slow-acting device.

3. In combination, a main section of railway track containing a switch, an approach section, a track circuit including a track relay for each section, a signal for governing traffic into said main section, an approach locking relay for the control of said switch, a slow-acting device having an energizing winding and a normally open contact, means for energizing the winding of said slow-acting device when said signal indicates stop provided that said approach locking relay is deenergized provided that the track relay for said main section is energized and the track relay for said approach section is deenergized, and means for preventing said approach locking relay from being energized unless said signal indicates stop and the track relay for said main section is deenergized or the track relay for said approach section is energized or the contact of said slow-acting device is closed.

4. In combination with a main section of railway track containing a switch, an approach section, a track circuit including a track relay for each section, a signal for governing traffic into said main section, an approach locking relay for the control of said switch, a slow-acting device having an energizing winding and a normally open contact, means for energizing the winding of said slow-acting device when said signal indicates stop if and only if said approach locking relay is deenergized and the track relay for said main section is energized and the track relay for said approach section is deenergized, and means for controlling said approach locking relay by said track relays and by the contact of said slow-acting device. 30 35 40

5. In combination, a main section of railway track containing a switch, an approach section, a track circuit including a track relay for each section, a signal for governing traffic into said main section, an approach locking relay for the control of said switch, a slow-acting device having an energizing winding and a normally open contact, means for energizing the winding of said slow-acting device when said signal indicates stop if and only if said approach locking relay is deenergized and the track relay for said approach section is deenergized, and means for controlling said approach locking relay by said track relays and by the contact of said slow-acting device. 45
